UNITED STATES PATENT OFFICE.

CHARLES D. McDONALD, OF CHICAGO, ILLINOIS.

SUCTION-CUP.

1,252,280.

Specification of Letters Patent.

Patented Jan. 1, 1918.

Original application filed March 17, 1917, Serial No. 155,449. Divided and this application filed August 23, 1917. Serial No. 187,868.

To all whom it may concern:

Be it known that I, CHARLES D. McDONALD, a citizen of the United States, residing at Chicago, in the county of Cook and State 5 of Illinois, have invented certain new and useful Improvements in Suction-Cups, of which the following is a specification.

The present invention relates to a suction cup more particularly adapted for use in 10 connection with automatic die-presses for separating the work from a pile and carrying it into position to be operated upon by a feeding mechanism, and is a division of my application Serial No. 155,449, filed 15 March 17, 1917, entitled "Work separating means".

The object of the invention is to make a flexible connection between the conduit and cup member so that the cup member may 20 adjust itself to different positions of angularity with respect to the conduit, whereby the cups attain a full and efficient contact with the surface of warped or other irregularly positioned sheets of work.

25 The invention further consists in the features of construction and combination of parts hereinafter described and claimed.

In the drawings:

Figure 1 is a vertical section of one of 30 the cups of the present invention, showing it attached to a conduit;

Fig. 2, a plan view of the parts shown in Fig. 1;

Fig. 3, an elevation, showing a plurality 35 of the cups engaged with an irregular sheet of work; and

Fig. 4, a view similar to Fig. 1, with the cup placed in angular position with respect to the conduit.

40 In the art to which the present invention relates, suction cup mechanisms are known which act upon a pile of work to separate the sheets thereof, one by one, and lift them singly into position to be engaged by the feed mechanism of an automatic die-press. Owing to the fact that these sheets of work are sometimes warped, or otherwise irregular, the suction cups will not gain full contact with the surface of the work, with the 45 result that a leakage occurs and the suction is broken, whereupon the work falls away from the cups, or from one of them, and is thereby not properly transported into posi-

tion for engagement by the feed mechanism. The present invention deals with a means 55 for overcoming this difficulty.

Referring now to the drawings, particularly to Figs. 1 and 3, the cup as there shown is formed with an outer member 5 in the form of a ring, with an inwardly 60 extending upper flange 6. The inner face of the outer member is threaded, and meshing with this thread is the exterior, threaded surface of an inner ring member 7. Interposed between the inner face of the flange 65 portion 6 and the upper face of the inner ring portion 7 is the edge 8 of a flexible diaphragm 9, formed of rubber or other suitable material. The inner edge of this diaphragm is clamped between a locking nut 70 10 and a flange 11 of a sleeve 12, which sleeve is exteriorly threaded to receive the locking nut 10; and fixedly secured to the sleeve 12 is a conduit member 13, in the form of a stiff tube, preferably of metal. 75

The diaphragm 9 is preferably made of rubber or other flexible material, and when in position closes the open upper end of the outer ring portion 5, and thus forms a top cover for the suction cup. The diaphragm 9, being of flexible material and secured at its outer and inner edges only, is capable of a flexing or yielding movement, whereby the cup structure comprising the outer section 5, the inner section 7 and the 85 diaphragm 9, may move into any desired angular position with respect to the conduit 13, as shown in Fig. 4.

By referring to Fig. 3, the use of the device in practice will be apparent. In this 90 figure there has been shown, on an exaggerated scale, a sheet of work warped out of flat condition. Two of the suction cups are in engagement with this sheet of work, and because of the presence of the flexible 95 diaphragm 9, the cup bodies have moved into an angular position with respect to the conduit, so that they obtain a firm and efficient engagement with the surface of the work, irrespective of its curved condition. 100

The device is extremely cheap and simple of construction and contains no parts that are liable to get out of order under ordinary conditions of use.

I claim:

1. A suction cup, comprising a metal ring

105

having a smooth lower face for engagement with the work, a conduit member in the form of a rigid pipe, a connection between the ring and conduit forming a closure for the upper end of the cup, and said connection being flexible to permit a universal movement between the ring and conduit to enable the ring and conduit to move into any desired position of angularity with respect to the conduit and obtain a firm engagement with irregular sheets of work, substantially as described.

2. A suction cup, comprising a metal ring having a smooth lower face for engagement with the work, a conduit member in the form of a rigid pipe, a flexible diaphragm in the form of a flat disk having a central opening, means for securing the outer edge of the diaphragm to the ring, means for securing the inner edge of the diaphragm to the conduit, said diaphragm forming a closure for the upper end of the ring and forming a flexible connection between the conduit and ring, permitting the ring to move to any desired position of angularity with respect to the conduit and obtain a firm en-

gagement with irregular sheets of work, substantially as described.

3. A suction cup, comprising an outer ring member having an inwardly extending flange at its upper end leaving a central opening at said upper end, an inner ring member having a threaded engagement with the inner wall of the outer ring member, a rigid conduit extending into said central opening, a flexible disk having a central opening, said disk being clamped at its outer edge between the upper face of the inner ring and the under face of said flange, clamping means associated with said conduit for engaging and clamping the inner edge of the flexible disk, and said disk when in position forming a closure for the central opening of said outer ring, and forming a flexible connection between the conduit and outer and inner rings to permit said rings to move into any desired position of angularity with respect to the conduit and the cup to obtain firm engagement with irregular sheets of work, substantially as described.

CHARLES D. McDONALD.
